UNITED STATES PATENT OFFICE.

WALTER H. SMITH, OF PITTSBURGH, PENNSYLVANIA, ASSIGNOR TO MILLER SAW-
TRIMMER COMPANY, A CORPORATION OF PENNSYLVANIA.

CORD-RETAINING MEANS.

1,386,537.

Specification of Letters Patent.

Patented Aug. 2, 1921.

Application filed April 8, 1919. Serial No. 288,626.

To all whom it may concern:

Be it known that I, WALTER H. SMITH, a subject of the King of England, residing at Pittsburgh, in the county of Allegheny and State of Pennsylvania, have invented certain new and useful Improvements in Cord-Retaining Means, of which the following is a specification.

This invention relates to an improvement in sheet retaining means, used in conjunction with the platen grippers of a platen press.

In the operation of a platen printing press, it is frequently necessary to supplement the action of the usual sheet grippers, in order that the printed sheet may be evenly drawn from the type, or the tendency of such sheet to stick to the type overcome, during the printing operation. Ordinarily, this supplemental gripping means has been supplied by the pressman tying the ends of one or more pieces of cord to the respective grippers, so that the cord may bear upon the sheet across and between the grippers. It is a comparatively difficult and slow operation to secure the cord in place with just the proper tension, particularly where one or more such cords are used.

The present invention is designed to provide a means, in the form of a clip, which may be readily applied to the grippers, and which is so constructed that when in place the usual retaining cord may be readily and quickly connected to such grippers, with just the proper degree of tension, and with materially less expense of time and labor than in the method heretofore practised.

In the drawings:—

Figure 1 is a plan view, illustrating the application of the improvement.

Fig. 2 is an enlarged broken plan of one of the clips in place, with one end of the cord secured thereto.

Fig. 3 is a section on line 3—3 of Fig. 2.

Fig. 4 is a section on line 4—4 of Fig. 2.

Fig. 5 is a section on line 5—5 of Fig. 2.

Fig. 6 is a plan illustrating the use of the clip as a means for securing a blocking-out strip to the gripper.

Fig. 7 is a section of the same.

This invention is here shown as applied to the grippers 12 and 13, of a platen press, which grippers are mounted ordinarily on the rocker bar 11, by bolts 14, and coöperate with the platen 10 of the press, in the usual manner. Ordinarily these grippers will

hold the sheet from being drawn from the platen as the type recede, but frequently the work on hand is of such a nature that additional transverse paper holding means must be used. Under the circumstances it has long been customary to secure a cord, as 18, to the respective grippers 12 and 13, by wrapping the end of the cord one or more times about the grippers and tying the same in place. This is not only a somewhat tedious operation, but where one or more cords are used, it is rather difficult to secure all such cords in place with even tension, and hence the slack cord will be of little advantage.

The retaining clips, shown at 16 and 17 in the drawing, are designed to provide a means to permit the necessary cords to be readily and quickly secured in position with their tension, during such application, under direct control, so that all cords will act evenly on the paper.

The improved clip, as here shown, comprises a plate 19, of substantial length, but of somewhat less width than that of the gripper. One edge of this plate is provided near each end thereof with spring tongues, formed by integral projections on the plate 19 which are bent upwardly at the edge of said plate, as at 20, 21, a distance substantially equal to the thickness of the gripper, and then projected rearwardly to form the spring sections 22, 23.

The edge of the plate 19 provided with the tongues, is also formed about mid-distance between said tongues with a cord engaging lip 25. This lip has a rounded outer edge, and its inner edge is integral with the plate 19 for a comparatively short length of inner edge, as at 24. The remaining portion of the inner edge of the lip is spaced from the edge of the plate 19, as at 26, forming a retaining slot, the walls of which slightly converge, as shown.

The improved clip is, as will be readily apparent readily and conveniently applied to the gripper, by forcing the clip over the inner edge of the gripper, so that said clip is retained on the gripper through the spring pressure between the tongues and plate. The clips are applied so that the cord engaging lip projects beyond the inner edge of the gripper, as shown in Fig. 1, and while the application of the cord to the clips may be carried out in any desired manner,

it is preferred that the cord, which may be knotted at one end if desired, to prevent slipping, is passed into the retaining slot 26 of the clip on one gripper, passed around the gripper from above, carried across to the opposite gripper, passed around the latter gripper from beneath and over and through the lip of the clip on such gripper. The free end of the cord is then passed over the lip of the particular clip, beneath the lip, up through the retaining slot 26, and the end carried laterally and forced beneath one of the spring tongues, by which it is securely held, all as particularly shown in Figs. 1 and 2.

The spring tongues are formed with a depending V-shape portion, to increase the spring effect.

One edge of one of the spring tongues is formed to provide a cutting edge 28, so that the free end of the cord when finally drawn beneath said spring tongues for holding, may be readily severed.

With use of the improved retaining clips it is apparent that the pressman can readily and conveniently position the cord or cords at any desired points lengthwise of the grippers, and that with the clips so positioned the work of securing the cords in place is extremely simple. With the clips the same tension can be readily and easily secured to all transverse cords in use, and considerable time may thus be saved. Furthermore it is apparent that even with the cords wrapped about the grippers the clips may be adjusted longitudinally of the grippers for some slight distance without materially affecting the cord connection. This is a decided advantage, which is practically impossible under the customary method of securing the cords in place.

Another and important function of the cord-retaining clips is that they permit the ready application and securing in position of the cardboard or paper strips usually employed in blocking out, as for example in blocking out the actuating levers of numbering heads when necessary. These blocking-out strips, as 30, have usually been glued or similarly secured to the underside of the grippers, but with the improved cord retaining clip, such blocking-out strips may be secured between the plate 19 and the lower surface gripper, the clip being applied from the relatively outer edge of the gripper, as shown in Fig. 6. Obviously, any number of such blocking-out strips may be applied to the gripper, and in any relative positions.

I have described and shown, in full detail, one form of device embodying my invention. It is to be understood, however, that the invention may be embodied in other forms, and that changes may be made in the particular form, which has been de-

scribed and shown, without exceeding the scope of the appended claims.

Having thus fully described my said invention, what I claim as new, and desire to secure by Letters Patent is:—

1. The combination with a pair of platen grippers, of cord retaining and locking clips, each clip open on one side to removably engage said gripper, and each clip having a cord engaging lip, and a cord extending around the lips and the gripper arms and locked under said clips. 70

2. The combination with a platen gripper, of a clip having spring tongues to engage the gripper, and cord locking means carried by the clip, and a cord engaging around the gripper and the clip and secured by the latter. 80

3. The combination with a platen gripper, of a clip having gripper embracing means, and a cord locking lip carried by and extending from the clip, and a cord engaging around the gripper and the clip and secured by the latter. 85

4. The combination with a platen gripper, of cord retaining means removably engaging said gripper, said cord retaining means being formed with a cutting edge. 90

5. The combination with a platen gripper, of a clip having spring arms to bear upon the gripper, and a cord engaging lip projecting from the clip, one of said arms serving to hold the free end of the cord. 95

6. A cord retaining clip for platen grippers including a plate, spring means carried by one edge of said plate, and a cord engaging lip carried by the said edge of the plate. 100

7. A cord retaining clip for platen grippers comprising a plate, spring tongues carried by one edge of and arranged in spaced relation to the plate, and a cord engaging lip carried by the said edge of the plate and formed to present a cord receiving slot with said edge. 105

8. A cord retaining clip for platen grippers comprising a plate, spring members carried by one edge of and spaced from the plate, and a lip projecting from one edge of the plate and formed to present a cord receiving slot with said edge, said lip being on a plane above the plate. 110

9. A cord retaining clip for platen grippers comprising a plate, spring tongues carried thereby, and a cord engaging lip carried by the plate, one edge of one of the tongues being sharpened to present a cord cutting edge. 120

10. The combination with a platen gripper, of a cord retaining and locking means removably engaging the gripper, and a cord to coöperate with said means and gripper to hold said means against accidental separation from the gripper. 125

11. The combination with a platen gripper, of a cord retaining clip open at one end 130

to slidably engage said gripper, and cord retaining means carried by the clip to be engaged with the cord after the latter has been passed beneath and around the gripper at 5 the open end of the clip.

12. The combination with a platen gripper, of a cord retaining clip having an open end to slidably embrace the gripper, and a closed end to bear against one wall of the 10 gripper, and cord retaining means carried

by the clip in position to receive the cord terminal after such cord has passed beneath and over the gripper in opposition to the closed end bearing of the clip on the gripper, whereby the cord serves to prevent accidental disengagement of the clip from the gripper. 15

In testimony whereof I affix my signature.

WALTER H. SMITH.
